UNITED STATES PATENT OFFICE.

SADIE DEBORAH GOLDISH, OF MARIETTA, OHIO.

INSECTICIDE HOLDER.

Application filed February 5, 1925. Serial No. 7,089.

My invention relates to holders for insecticides in solid form and has for its object to provide a holder which will permit free volatilization of the insecticide and at the same time will prevent contact of the solid insecticide with the garment or other article to be preserved from the attacks of insects and will prevent waste of the insecticide.

For the purpose of preventing moths from laying eggs in garments or other articles of silk, fur or wool or formed of fabrics containing silk or wool, camphor either natural or synthetic has long been used in solid form, the camphor volatilizing slowly and the emanations given off having the effect of keeping the moths away. Various other volatile substances capable of giving off emanations which repel moths are used in place of camphor, the most common compound for this purpose being known as mothballs. In the use of camphor or mothballs it has been common to place the solid insecticide in the pockets or folds of the garments or other article to be protected from moths. When the garments or other articles are unwrapped the unevaporated residue of the insecticide is liable to be wasted or if it remains in pockets of garments keeps the garment impregnated with the odor of the insecticide when worn.

In order to prevent waste of the insecticide and to avoid having the insecticide in direct contact with the article to be protected as well as to avoid having the garment or other article carry with it any of the insecticide after it is unwrapped for use, I have devised the holder of my present invention by which the solid insecticide may be so held as to permit it to give off its emanations freely while it cannot come in direct contact with the garments or other articles and so that any portion of the solid insecticide which may remain after the garments or other articles are taken out for use, will be retained for further use.

It is the object of my invention to provide a holder for solid insecticides which will be simple, inexpensive and effective for the purposes above stated.

Referring to the drawings:

Figure 1 is a side view of one form of my holder.

Figure 2 is a cross sectional view on line 2-2 of Figure 1.

Figure 3 is a front view, partly broken away, of my holder arranged in a bag.

Figure 4 is a vertical sectional view on line 4-4 of Figure 3.

Figure 5 is a cross sectional view on line 5-5 of Figure 6 and

Figure 6 is a front view of a sheet for wrapping articles having my holder applied thereto.

In the drawings 1 indicates a holder for mothballs, and like insecticide materials in solid form, adapted for use in closets by stretching it along over the hooks on which garments may be hung. This holder as shown consists of a strip of cheese cloth or like relatively loosely woven fabric folded to form a tube and having its edges stitched together. If laid along and resting on the garment supporting hooks the mothballs, or other solid insecticide material indicated as 2 should be distributed at suitable distances apart as indicated in Figure 1 so as to afford sources of evaporation of the volatile material at substantially equal distances apart. It is essential that only a portion of the tubular holder thus formed be of loosely woven fabric. If desired it may be formed of a strip of cheese cloth and a strip of closely woven cloth. The cheese cloth or other loosely woven material holds the moth balls, or other solid insecticide material, from contact with the garments and from falling to the floor to possibly be crushed into fragments. At the same time the open weave of the cheese cloth affords opportunity for free escape of the volatile insecticide.

In Figures 3 and 4 my invention is shown applied to a bag adapted to receive and store articles such as furs, woolen garments and other articles formed in whole or in part of fur, wool, silk or other material on which the larvae of the moth or other destructive insects feeds. 3 indicates the front of the bag, shown in Figure 3 as partly broken away, 4 indicates the back of the bag and 5 indicates loops by which the bag may be conveniently suspended. This bag is formed from a sheet of closely woven fabric by folding the sheet and stitching its sides and ends together. Secured to the back 4 of this bag by rows of stitching 7 are strips 6 of cheese cloth or like loosely woven material. These strips 6 preferably extend to the bottom of the bag and form separate receptacles for mothballs or other solid insecticide, these receptacles being closed at their lower ends by a cross line of stitching

8 the receptacles being left open at the top for insertion of the insecticide material. When the bag is hung from the loops 5 the mothballs or other solid insecticide 2 will 5 tend to accumulate at the lower ends of the receptacles.

In the embodiment of the invention shown in Figure 6 the strips 6 are secured to a sheet of material 9 corresponding to the back 4 10 of the bag shown in Figure 3, the front 3 of the bag being omitted. In this form the device is adapted to be hung against the wall of a closet or wardrobe or may be folded or wrapped about the articles to be 15 protected from moths. When so used the loops 5 may be omitted.

The material of the front 3 and back 4 of the bag, or of the sheet 9 may be of any suitable material which is not attacked by 20 moths. I prefer to use for this purpose cloth woven of cotton or linen closely woven so as to afford a firm support for the receptacles 6 to prevent the passage through it of the moths. For bags such as shown in Figures 25 3 and 4 it is particularly desirable if cloth is used that it be so closely woven as to offer considerable resistance to the volatiles given off by the mothballs, and if it is desired to retain the volatiles within the bag

the cloth of which it is formed may be rendered impervious by any usual water proofing means. Paper of such toughness as to hold the stitching by which the strips 6 forming the receptacles for the mothballs may be used for the bags or the wrappers. 30 35

The bags to the back of which the strips 6 are secured may be of any convenient form and may be closed at their ends by any convenient means.

Any insecticide in solid form adapted to 40 give off emanations repellent to insects may be used instead of camphor or mothballs.

Having thus described my invention what I claim is:—

A bag for articles to be protected from 45 moths formed of closely woven fabric and open at its upper end, having on the inner face of its back portion pockets open at their upper ends adapted to contain moth balls 50 formed by strips of loosely woven material extending from the bottom of the bag to the upper edge of the back portion so that moth balls may be introduced into the pockets without disturbing the articles to be protected contained in the bag. 55

In testimony whereof, I hereunto affix my signature.

SADIE DEBORAH GOLDISH.
